UNITED STATES PATENT OFFICE.

VITAL QUENON, OF TURTLE CREEK, PENNSYLVANIA.

WRENCH.

SPECIFICATION forming part of Letters Patent No. 761,996, dated June 7, 1904.

Application filed April 19, 1904. Serial No. 203,872. (No model.)

To all whom it may concern:

Be it known that I, VITAL QUENON, a subject of the King of Belgium, residing at Turtlecreek, in the county of Allegheny and State of Pennsylvania, have invented certain new and useful Improvements in Wrenches, of which the following is a specification, reference being had therein to the accompanying drawings.

- 10 This invention has relation to monkey-wrenches, and has for its object the provision of a wrench of novel form and construction having double jaws—that is, two stationary jaws and two movable jaws—the two stationary jaws being held in fixed position relatively to the handle of the wrench and the two movable jaws being provided with means whereby they may be adjusted relatively to the fixed jaws and rigidly held at the point to which 20 they are adjusted.

My invention consists in the novel construction, combination, and arrangement of parts hereinafter described and claimed.

In the accompanying drawings, illustrating 25 my invention, Figure 1 is a side elevation of a wrench embodying my improvements. Fig. 2 is an edge view of the same. Fig. 3 is a longitudinal sectional view. Fig. 4 is a perspective view of a part of the shank with the 30 fixed and movable jaws removed therefrom. Fig. 5 is an edge view of the movable jaws. Fig. 6 is a perspective view of the fixed jaws removed from the shank, and Fig. 7 is a transverse sectional view on the line $\alpha\alpha$ of Fig. 1.

35 The fixed jaws 1 2 are composed of a single piece of metal, which is formed with grooves 3 3, that receive the upper ends of the square bars 4 4, four in number, which constitute the shank of the wrench, and the jaws 1 2 are 40 secured to the bars by rivets 5 5 after the movable jaws have been placed in position, as will be presently described. The bars 4 4 merge near their lower ends, forming two plates 6 6, and these plates merge into the 45 section 7, that terminates in a tang 8, which passes through the handle 9. The two sliding jaws 10 11 are formed integral with a rack-bar 12, which is T-shaped in cross-section and is formed with teeth 13, which are 50 engaged by teeth 14 on the inner side of a lever 15, which is pivoted at 16 between the two plates 6 6, the lower end of this lever being

pressed outwardly by a spring 17, secured at 18 to the shank.

The parts of the wrench being constructed 55 as described and shown are put together in the following manner: The movable jaws and the rack-bar are inserted in position between the bars 4 4, and the fixed jaws are then placed in position between the bars 4 4 and 60 the rivets 5 5 inserted to hold the fixed jaws in position. The movable jaws can be adjusted to any position merely by pressing the lower end of the lever 15, which is indented and roughened, as shown at 19, and then sliding the movable jaws up or down to the desired position and then releasing the lever 15, the upper end of which will be impelled inwardly by the spring 17, thereby causing the teeth 14 on the lever to engage the teeth 13 of 70 the rack-bar 12.

Having described my invention, I claim—

1. In a monkey-wrench, the combination with a shank composed of four bars, of fixed jaws having grooves adapted to receive said 75 bars, movable jaws carried on a rack-bar, said rack-bar being slidably mounted between said bars, and a pivoted lever formed with teeth and adapted to engage said rack-bar.

2. In a monkey-wrench, the combination of 80 a shank composed of four parallel bars, a fixed jaw secured to said bars, a T-shaped rack-bar fitting between said bars and having a rack on one side, and a pivoted lever adapted to engage the teeth on said rack-bar. 85

3. In a monkey-wrench, the combination with a shank composed of four square bars spaced apart, and a fixed jaw secured to the ends of said bars and having two engaging ends, of a movable jaw having two ends 90 adapted to coact with the engaging ends of a fixed jaw, a T-shaped rack-bar carried by said movable jaw, the rack thereon projecting between two of said bars, and a lever pivotally arranged between two of the bars and having 95 teeth adapted to engage the teeth on said rack-bar.

In testimony whereof I affix my signature in the presence of two witnesses.

VITAL QUENON.
